UNITED STATES PATENT OFFICE

102,596

DESIGN FOR A RANGE

Arthur Stockstrom and Almer H. Brodbeck, St. Louis, Mo., assignors to American Stove Company, St. Louis, Mo., a corporation of New Jersey

Application August 4, 1936, Serial No. 64,245

Term of patent 14 years

To all whom it may concern:

Be it known that we, Arthur Stockstrom and Almer H. Brodbeck, citizens of the United States, residing in the city of St. Louis and State of Missouri, have invented a new, original, and ornamental Design for a Range, of which the following is a specification, reference being had therein to the accompanying drawing forming part thereof.

The accompanying drawing is a perspective view of a range, showing our design.

The opposite side or end is substantially like the end shown in the drawing.

The characteristic features of our design reside in the centrally disposed top member provided with a rectangular depressed portion of substantially the proportions shown.

We claim:

The ornamental design for a range as shown and described.

ARTHUR STOCKSTROM.
ALMER H. BRODBECK.
